CLAIM

The ornamental design for a flanged sleeve connector for a secure enclosure in a secure conduit system, as shown and described.

DESCRIPTION

FIG. 1 is a front perspective view of a flanged sleeve connector for a secure enclosure in a secure conduit system, showing my new design;

FIG. 2 is a rear perspective view thereof;

FIG. 3 is a first end elevation view of my new design;

FIG. 4 is a right side elevation view thereof, the left side elevation view being a mirror image thereof;

FIG. 5 is a second end elevation view thereof; and,

FIG. 6 is a side elevation view thereof in which the flange connector is secured to a secure enclosure and the broken line showing of the enclosure is for illustrative purposes and forms no part of the claimed design.
